UNITED STATES PATENT OFFICE.

EDWIN R. BULLOCK, OF PAWTUCKET, RHODE ISLAND.

DESIGN FOR A SPOOL-CABINET.

SPECIFICATION forming part of Design No. 18,388, dated June 19, 1888.

Application filed April 27, 1888. Serial No. 272,078. Term of patent 7 years.

To all whom it may concern:

Be it known that I, EDWIN R. BULLOCK, a citizen of the United States, residing at Pawtucket, in the county of Providence and State of Rhode Island, have invented and produced 5 a new and original Design for Spool-Cabinets, of which the following is a specification, reference being had to the accompanying drawings, forming part thereof.

Figure 1 is a half front and half rear elevation of my newly-designed spool-cabinet, and Fig. 2 is a side elevation of the same. These two views fully illustrate the design.

Cabinets for holding spooled cotton, silk, 15 linen, &c., have heretofore been made rectangular in outline, resembling small bureaus, which they are sometimes called.

My design consists in making the cabinet cylindrical and its external appearance an enlarged model, both in form and color, of a spool wound, except that one head will show the ends of drawers or trays with the pulls, and the spool will rest on a base, as shown.

Referring to the drawings, A represents half the front head. 25

B represents half the back head, showing ends of drawers or trays.

C indicates the body of the spool, which is cored.

D represents the base on which the spool 30 rests, consisting of two end pieces and two side pieces, as shown.

I claim—

The design for a spool-cabinet herein shown and described, the same having a general form 35 of a cylinder and presenting to the eye the appearance of a large spool wound, showing on one head the ends of drawers or trays with their pulls, and supported on a base, as shown and described.

EDWIN R. BULLOCK.

In presence of—

SAMUEL M. CONANT,
HENRY H. DAVISON.
